UNITED STATES PATENT OFFICE

170,431

AUTOMOBILE AIR COOLER

William J. Stolz and Alfons Glassenhart,
Phoenix, Ariz.

Application April 6, 1953, Serial No. 24,379

Term of patent 14 years

(Cl. D62—4)

To all whom it may concern:

Be it known that we, William J. Stolz and Alfons Glassenhart, have invented a new, original, and ornamental Design for an Automobile Air Cooler, of which the following is a specification, reference being had to the accompanying drawing, forming a part hereof.

Fig. 1 is a perspective view showing the top, front and right side of an automobile air cooler, embodying our new design.

Fig. 2 is a top plan view of the automobile air cooler shown in Fig. 1.

Fig. 3 is a front elevation of the automobile air cooler shown in Fig. 1.

Fig. 4 is a side elevation of the automobile air cooler shown in Fig. 1.

The left side and back are like the respective right side and front shown.

We claim:

The ornamental design for an automobile air cooler, as shown and described.

WILLIAM J. STOLZ.
ALFONS GLASSENHART.
